Inventor: Harry J. Gutman,
By Thomas G. Orrig, Atty.

UNITED STATES PATENT OFFICE.

HARRY J. GUTMAN, OF DES MOINES, IOWA.

INCANDESCENT-LAMP SOCKET.

SPECIFICATION forming part of Letters Patent No. 447,315, dated March 3, 1891.

Application filed September 29, 1890. Serial No. 366,571. (No model.)

To all whom it may concern:

Be it known that I, HARRY J. GUTMAN, a citizen of the United States of America, residing at Des Moines, in the county of Polk and State of Iowa, have invented a new and useful Improvement in Electrical Connections, of which the following is a specification.

My object is to provide an electrical connection which shall be cheap, durable, and compact in form, adapted for use at street intersections in the connection of lamps in circuit, and, in fact, in every case where it is found necessary to detachably couple together the severed ends of an electric circuit.

My object, further, is to provide means by which when the connection is employed with a working resistance the latter may be readily and effectively cut in and out of circuit. In order to accomplish these results and produce a practical coupling, it is necessary that the contact should be relatively perfect, that the continuity of the insulation should be preserved at the connection, that the parts connected should be securely held together in order to maintain perfect contact, so that short-circuiting cannot occur. It is also necessary that the completed connection should be small in size and capable of ready attachment and detachment.

My invention, in conjunction with an incandescent lamp, consists in an interior connecting portion, to which the main leads are secured, an outer jacket-piece surrounding the interior portion, which latter is chambered at its lower end portion to receive the upper cylindrical portion of the lamp, the entering-leads being electrically connected with plate-pieces on the interior of the chambered portion. The upper portion of the lamp has vertical moving plugs or pins surrounded by a yielding pressure, said plugs being electrically connected with the filament of the lamp. Fixed to one of said pins or plugs is a thumb-piece within an angular slot in the casing of the lamp.

My invention consists, further, in certain details of construction and arrangement of parts, hereinafter more fully described and set forth, reference being had to the accompanying drawings, in which—

Figure 1 is an enlarged vertical section.

Fig. 2 is a side elevation, showing the parts about to be joined. Fig. 3 is an enlarged detail view of one of the metallic casings. Fig. 4 is a side elevation showing the angular slot. Fig. 5 is a detail cross-sectional view on the line $\alpha\alpha$, Fig. 4.

I have shown my improved connection as applied to an incandescent lamp; but it will appear hereinafter that its utility is not limited to this application alone.

A represents the main leads, which are secured by binding-screws $\alpha\alpha$ to the angular metallic connections $a'a'$, Fig. 1, the upper arms of which are held against a divisional insulating-plate B—preferably of vulcanite— integrally formed with the vulcanite interior portion B^2 , the lower arms of said angular connections $a'a'$ being also held upon the upper face of said interior portion B^2 .

B^3 is a cap-piece secured to the divisional plate B.

Secured to the lower arms of the angular connections $a'a'$ are wires $b b$, which extend downwardly through the vulcanite of the interior portion B^2 , and are connected at their lower extremities to contact-plates C C, which are exposed and held within an annular chambered part of the interior portion B^2 . The interior or insulating portion B^2 is exteriorly surrounded by a removable metallic jacket or casing D, having formed thereon a flanged and slotted rim b'' , said slot being shown in the enlarged view, Fig. 1. This removable casing or jacket D is held upon the interior portion by means of the screw d , which travels within a slot, as shown in Fig. 2. The lamp E is secured in the usual manner to the part F^2 , which latter has vertical bores $e e$ extending therethrough, metallic casings $e' e''$ being inserted within said vertical bores $e e$, one of said casings being shown in detail in Fig. 3. I also provide pins or plugs $f f'$ and contact-buttons $H H^2$, each of said plugs or pins being located, respectively, within the vertical bores $e e$ and each surrounded by spiral springs $h h'$. (Shown more clearly in Fig. 1.) These metallic casings are slotted, as shown in Fig. 3, at h'' , and thus adapted to permit transverse pins h''' , secured to the lower ends of the said pins or plugs $f f'$ to travel in said slots h'' , and thus limit the extreme upward normal movement of the said

plugs $f'f''$ and buttons $H H^2$, when the two parts are not joined. The pin attached to the contact-button H terminates at the end of its casing e , while the pin f' is extended below the end of its casing e and is bent at right angles, its extending arm being screw-threaded and thus adapted to permit the attachment of a finger-piece H^3 , which latter travels within and is held by an approximately angular slot H^4 . (Shown clearly in Fig. 4.)

J are pins extending from each side of the periphery of the upper portion of the part E^2 , Fig. 5, and are adapted to be inserted within the vertical slots j , Fig. 2, formed on each side of the casing D and in the insulating material, said slots extending from the lower edge of the upper part to the slot in the flanged rim b'' .

20 The platinum leads to the filament are connected to the metallic conducting casings.

If desired, the finger-piece H^3 may be made of insulating material.

The union of the two parts, the upper one 25 of which consists of the interior portion B^2 and the removable casing D , holding the leads to be connected in circuit, and the lower part E^2 , is effected as follows: The lugs J of said part E^2 are inserted within the vertical slots j in the upper part, the upper portion of part E^2 being within the lower chambered portion of the upper part, and when the lugs J reach the point of coincidence with the slot in flanged rim b'' the lower part may then be 35 turned or rotated in either direction forming a bayonet-joint connection. The buttons of the plugs or pins $H H^2$, extending slightly beyond the meeting face of the part E^2 when the latter is inserted within the chambered part of the interior portion B^2 , impinge against the contact-plates $C C$, and thus compress the springs $h h'$, which cause the buttons of the pins $H H^2$ to bear against said plates and maintain contact. The circuit with platinum leads of the lamp is now 45 completed from the main leads through angular connections $a' a'$, wires $b b$, contact-plates $C C$, buttons and pins $H H^2$, springs $h h'$, and casings $e e''$.

50 It is apparent that any other working resistance may be connected in circuit by my device, or that the severed portions or ends of a wire may be united together as well as a lamp.

55 Referring to Fig. 1, it will be seen that the severed ends of a circuit are connected or coupled together, and that in this case I form and construct both the pins $H H^2$ in the same manner and dispense with the finger-piece H^3 and provide cap-pieces B^4 , which are adapted to be screwed upon the solid vulcanite portions.

When the lamp-socket is coupled by the bayonet-joint connection, the two buttons H and H^2 , respectively, contact with the plates $C C$, thus completing the circuit through the

filament of the lamps, the plugs $f'f''$ and the buttons $H H^2$ being in the highest position assumed when the two parts are joined, the finger-piece H^3 being within the vertical portion of the angular slot H^4 and near the upper extremity thereof, the springs $h h'$ being compressed. When the two parts are disconnected, the buttons $H H^2$ and plugs $f'f''$ advance vertically slightly, the finger-piece H^3 being then at the said extremity of the vertical portion of the slot H^4 , which is uniform in length with the slot h'' .

Assuming the parts to be joined and contact made, in order to cut or break connection the operator depresses the finger-piece H^3 , engaging the latter in the horizontal portion of the angular slot.

Having thus described my invention, what claim as new, and desire to secure by Letters Patent, is—

1. In a combined electrical connection and switch, the two meeting sections, one of which is provided with contact-plates to which the main leads are electrically connected, the other part having plugs or pins acted upon by yielding pressure, one of said pins having secured thereto an actuator operated from the exterior and held by an approximately angular slot to break contact, as and for the purposes set forth.

2. In a combined electrical switch and contact, the combination of meeting parts or sections, one of which has a slotted chambered portion, contact-plates electrically connected with the main leads, and an exterior casing having slots, the other one of said parts or sections having lugs adapted to enter the slots of the chambered part of the interior portion and casing and having also beveled bores which are metallically lined, pins or plugs within said bores acted upon by yielding pressure and normally bearing against the contact-plates when the connection is effected, one of said pins or plugs having a finger-piece traveling within an approximately angular slot, to operate as and for the purposes set forth.

3. In an electrical connection, the two parts or sections to which the leads of the circuit are respectively connected, having contact-plates electrically connected through insulating material with said leads carried by one part or section, and movable contact-plugs having buttons thereon adapted to contact with the plates carried by the other part or section, slotted metallic bores embedded in insulating material, pins adapted to travel within the slots of the bores, and spiral springs surrounding the contact-plugs, together with a bayonet-joint connection between the two parts or sections, as set forth.

HARRY J. GUTMAN.
